Greggton, Tex.

Application November 11, 1937, Serial No. 174,071

13 Claims. (Cl. 166—10)

This invention relates to a well tester.

An object of the invention is to provide a testing tool adapted to be lowered into a well and whereby a sample of the fluid in the formation to be tested may be entrapped and removed to the ground surface for inspection.

It is another object of the invention to provide a testing tool of the character described designed to be attached to the lower end of the drill stem or other tubular string and lowered into the well empty and embodying novel means for forming a seal above the formation to be tested and a novel type of valve normally closing the lower end of the drill stem, or other operating string and adapted to be opened by a relative longitudinal movement of the valve means to permit the entrance of a sample from the formation beneath the seal with means for automatically entrapping the sample upon upward movement of the tool.

It is another object of the invention to provide a testing tool of the character described whereby the heavy drilling fluid may be allowed to enter the drill stem, or other operating string as the tool is withdrawn, in the presence of gas pressure in the well, to prevent a blowout.

Another object of the invention is to provide a well tester of the character described wherein provision is made for maintaining the operating string empty while going into the well but which will allow circulation of drilling fluid through said string, while going in or coming out, if gas pressure conditions make such circulation advisable.

A further object of the invention is to provide a tester of the character described embodying an expandible packer and having means for preventing the premature expansion of the packer.

A still further object of the invention is to provide a tool of the character described whereby the circulation may be reversed, that is liquid may be forced down through the drill stem and out into the bore above the packer, and vice versa.

With the above and other objects in view the invention has particular relation to certain novel features of construction, operation and arrangement of parts, an example of which is given in this specification and illustrated in the accompanying drawings, wherein—

Figure 1 shows a vertical, sectional view of the upper end of one form of the testing tool in closed position preparatory to be lowered into the well and showing a downwardly opening valve therein.

Figure 2 shows a vertical, sectional view of the lower end of the device shown in Figure 1.

Figure 3 shows a cross-sectional view taken on the line 3—3 of Figure 2.

Figure 4 shows a side view of a complete tool illustrating another embodiment shown in open position for the admission of a sample.

Figure 5 shows an enlarged, fragmentary, vertical, sectional view of the tool showing the valve mechanism open as shown in Figure 4.

Figure 6 shows an enlarged, fragmentary, vertical, sectional view of the lower end of either form of the tool in position for taking a sample, and

Figure 7 shows a fragmentary, vertical, sectional view showing the valve mechanism in position to admit drilling fluid from the bore into the drill stem or operating string.

Referring now more particularly to the drawings wherein like numerals of reference designate the same parts in each of the figures, the numeral 1 designates the body of the tool, screwed into the upper end of which there is the gland 2 whose upper end is upwardly tapered. The lower end of the body is reduced in inside diameter forming a bearing 3 through which the releasing tube 4 is slidably fitted. The lower end of the releasing tube extends beneath the lower end of the body and both the body and releasing tube have suitable perforations as 5, 6 providing for the inlet of a sample from the formation being tested. The upper end of the body 1 is inwardly thickened forming a bearing 7 through which the upper end of the releasing tube is fitted. Above the bearing 1 the body has the inside annular recess 8 to receive the dogs 9 which are seated against the coil springs 10. These coil springs normally hold the dogs inwardly as indicated in Figure 2 and the inner sides of these dogs have upwardly pitched ratchet teeth 11. The lower end of the dogs are flared downwardly and outwardly forming downwardly flared faces 12 against which the upper end of the releasing tube bears. The releasing tube is fitted closely through the bearings 3 and 7 so that it will be held in place by friction, while the tool is being lowered into or withdrawn from the well.

There is an expandible packer 13 whose lower end is suitably secured to the upper end of the gland 2 in any preferred manner. As shown in Figure 5 it is so secured by wrapping the same with securing wire 14.

The upper end of the packer 13 is securely attached, in any preferred manner to a coupling 15. A cylindrical housing 17 is screwed into the

coupling 15 and contains a cylindrical chamber 18. The upper end of the housing has an internally threaded box 19 into which the lower end of the drill pipe, or other tubular operating string, 20 is threaded. Said string 20 extends to the ground surface. Beneath the box 19 the housing is provided with the inwardly extended bearing flange 21 through which the upper end of a tubular mandrel 22 is fitted. The mandrel 22 is closely surrounded by a packing 23 countersunk into the flange 21. The lower end of the mandrel 22 is screwed into the housing 17 at the lower end of the cylindrical chamber 18 as clearly shown in Figures 1 and 5, said mandrel thus extending axially through the cylindrical chamber 18. In the embodiment shown in all of the figures, the mandrel has a transverse web 24 intermediate its ends and above and beneath said web the mandrel has the upper and lower side ports 25, 26 and in the embodiment shown in Figure 1 the web 24 has the downwardly opening valve 24a therein.

Slidably mounted on the mandrel 22 is the cylindrical shaped piston valve 27 having the piston rings 28, 29 therearound forming seals with the walls of the chamber 18. The piston valve 27 has an inside annular groove, or recess 30 therearound of a sufficient length to communicate with both of the ports 25, 26 when the valve mechanism is opened to admit a sample as shown in Figure 5. The piston valve also has an inside annular packing 31 forming a seal with the mandrel 22 and beneath the piston valve there is a packing 33 which is fitted closely around said mandrel and which fits closely within the chamber 18.

There is a piston, designated generally by the numeral 34 on the valve 27 and which is fitted closely around the mandrel 22 and closely within the chamber 18 and which may be formed of alternately arranged packing rings and spacing rings as shown in Figures 1, 5 and 7. Interposed between this piston 34 and the inwardly extended flange 21 and surrounding said mandrel there is a strong coil spring 35, shown more clearly in Figures 1 and 5. The housing 17 has its lower end reduced and formed into a tubular extension 36 which works axially through the gland 2 and which is surrounded by the packing 37 countersunk into said gland.

Attached to the lower end of the extension 36 there is an elongated tubular ratchet member 38 provided with the external ratchet teeth 39 which engage with the ratchet teeth of the dogs 9, when the valve mechanism of the testing tool is in closed position as shown in Figures 1 and 2, and prevent the premature setting of the packer.

The packer 13 encloses a chamber 40 and the ducts 41 lead from said chamber upwardly through the lower end of the housing and enter the lower end of the cylindrical chamber 18. The chamber 40 is normally filled with a suitable liquid as shown in Figure 1.

In order to make a test the apparatus is assembled as shown in Figure 2 with the piston valve 27 in its lowermost position so that the upper ports 25 of the mandrel will be closed to prevent drilling fluid from entering the drill stem, or operating strings while the tool is being lowered and with the lower ports 26 in registration with the groove 30. The piston valve 27 also has an outlet port 42 which registers with the outlet duct 43 through the housing 17, when the tool, in closed position, as shown in Figure 1 so that while lowering the tool through the drilling fluid into the

well the drilling fluid beneath may pass upwardly through the channel 44 of the housing extension and out through said ports 26, 42 and 43.

When the tool lands on bottom the downward movement of the releasing tube 4 will stop but the housing 17 and the body 1 will move on downwardly, the upper end of the releasing tube contacting with the diverging faces 12 and expanding the dogs 9 to release them from the ratchet teeth 39, placing the springs 10 under compression. The weight will thereupon be assumed, in part, by the packer 13 and an endwise compressive force will be exerted against said packer expanding it out against the wall of the bore, as shown in Figures 4 and 5, and compressing it inwardly so as to reduce the capacity of the chamber 40. The ducts 41 and that portion of the chamber 18 beneath the packing 33 will also be filled with fluid, as shown in Figure 1. When the pressure on the fluid in the chamber 40 is greater than the pressure of the drilling fluid outside of the tool (and which enters the groove 30 through the ports 43, 42, see Figure 1) the piston valve 27 and piston 34 will be forced upwardly on the mandrel 22 and place the spring 35 under compression. This spring 35 has sufficient resistance to react against said pressure fluid in the chamber 40 to cause the packer to expand and firmly seat against the walls of the bore to form a seal. Any fluid in the cylindrical chamber 18 above the piston 34 will be expelled outwardly through the side port 45 at the upper end of said chamber 18. This upward movement of the piston valve 27 will close the ports 42 and 43 and will uncover the ports 25 so that both the ports 25 and 26 communicate with the groove 30. The drilling fluid above is now sealed off from the strata to be tested and any fluid in said strata may flow inwardly through the ports 5 and 6 and up through the channel 44 and may pass through the ports 26, 25 around the partition 24, or valve 24a, and on up into the empty drill stem 20. The operator of the tool will be able to hear the fluid thus flowing up into the drill stem and will promptly stop the downward movement of the stem and will hold the stem stationary for the required length of time to permit the sample to enter the drill stem. When the sample has been taken the drill stem may then be elevated thus releasing the compressive force on the packer 13 and the spring 35 will thereupon force the piston valve 27 back downwardly into the position shown in Figure 1 closing the ports 25 to entrap the sample and the tool may then be withdrawn from the bore for an inspection of the sample.

At times the gas pressure in the well is liable to cause a blowout if the string is withdrawn from the well empty. As the string is withdrawn the top sections will be broken out one at a time so that the weight of that portion of the string left in the hole is not sufficient to overcome said pressure and the string is liable to be expelled from the well by said pressure. Therefore if there is any considerable gas pressure in the well after the test is taken and before the string is withdrawn the weight of the string should be released to allow it to travel further downwardly and the pressure of the liquid beneath the valve piston is raised sufficiently to move the piston valve 27 further upwardly, further compressing the spring 35 and until the ports 26 are completely covered and the port 42 is brought into registration with the radial bore 46 of the housing 17 as shown in Figure 7 and with the ports 25 still in registration with the groove 30. The

drilling fluid may then enter through the ports 48 and 42 and the groove 30 and the ports 25 into the drill stem and will fill said drill stem. The drilling fluid will thus be lowered, which may be noted by the operator and thereupon additional drilling fluid should be pumped into the well to keep the space between the drill stem and the walls of the well filled and to replenish the supply outside of the drill stem as it flows into and fills the empty drill stem. The well will thus be kept completely filled with the heavy drilling fluid as a guard against a blowout as the drill stem is withdrawn. This will not in any way contaminate the sample in the drill stem since the sample, if oil, can be measured as it comes through the release valve, in the derrick, controlling the upper end of the drill stem or the fluid may be allowed to run into the surface pit and there gauged.

While the tool is being lowered into the well, if conditions should require it, drilling fluid may be forced downwardly through the operating string 20 past the valve 24a and on down and out through the openings 6 and 5 and back up on the outside of the operating string so that circulation of the drilling fluid may be maintained, if desired, while lowering the tool. It is also obvious that in a similar manner circulation may be maintained, if desired, while withdrawing the tool from the well.

The drawings and description disclose what is now considered to be a preferred form of the invention by way of illustration only, while the broad principle of the invention will be defined by the appended claims.

What we claim is:

1. A well tester comprising a tubular string adapted to be lowered into a well to be tested containing drilling fluid, valve means movable to one position to close the lower end of the string, means for forming a seal between the string and the walls of the well bore to exclude the drilling fluid from the formation to be tested, means for actuating the valve means into open position to permit the entrance of a sample from said formation, beneath the sealing means, into the string, means for moving the valve means to another position to open the lower end of the string to the well bore, above said sealing means, to permit the entrance of drilling fluid into the string and means for moving the valve means to original position to again close the lower end of the string to entrap the contents thereof, therein.

2. A well tester comprising a tubular string adapted to be lowered into a well to be tested containing drilling fluid, a testing tool on the lower end of the string embodying relatively movable parts having an inflow conduit communicating with the interior of the string, means adapted to be compressed by relative movement of said parts for forming a seal with the walls of the well bore to exclude drilling fluid from the formation to be tested, valve means within the tool above the sealing means for controlling said conduit and normally closing the same to exclude the drilling fluid from the string while the tool is being lowered, said valve means being arranged to be opened upon such relative movement to permit the entrance of a sample from the formation into the string and means for closing said valve means to entrap said sample upon relative movement of said parts in another direction.

3. A testing tool, shaped to be lowered into a well and having a conduit therethrough and comprising relatively movable parts, means, contain-

ing a liquid, for forming a seal with the walls of the well bore and arranged to be compressed into such sealing relation by relative movement of said parts in one direction, valve means normally closing said conduit and arranged to be actuated by pressure of said liquid, upon such relative movement, into position to open the conduit and means effective to close the valve means when said parts are relatively moved in the other direction.

4. A testing tool having an inflow conduit therethrough and shaped to be lowered into a well and comprising relatively movable parts, means normally locking said parts against relative movement, means for forming a seal with the walls of the well bore and arranged to be compressed into said sealing relation upon such relative movement, means for releasing said locking means to permit such relative movement, valve means normally closing said conduit and arranged to be actuated, upon such relative movement, by the pressure of a liquid contained in the tool into position to open said conduit to permit the flow of a sample through said conduit and means for actuating the valve means to closed position upon relative movement of said parts in another direction.

5. A device of the character described comprising a tubular string of pipe shaped to be lowered into a well and having relatively movable parts, means normally closing the passageway through the string to permit the string to be lowered into the well empty sealing means on the string containing a chamber filled with fluid and adapted to form a seal between the string and the walls of the well bore, said relatively movable parts being effective, when relatively moved in one direction to apply compression to the liquid in said chamber to cause the expansion of the sealing means into said sealing relation with the walls of the well.

6. In a device for use in a well shaft, a packer body having a passage therethrough communicating the zone of the well shaft at opposite sides of the packer, valve means to close said passage, and a flow line forming said passageway and extending from below said packer to the well surface having a port therein opening into the well shaft, means to close the bore of said line, means to close the port in said line and communicate the zone of the bore of said line at opposite sides of said last-named means, and resilient means to resist actuation of said last-named means.

7. In a device of the character described adapted for use in a well, a flow line comprising relatively telescopic upper and lower portions, said upper portion having a bore, means to close said bore to the passage of pressure fluid therethrough in either direction, said upper portion having ports communicating with the well below said closure means, and means for closing the ports and opening the bore of said flow line to the passage of pressure fluid upwardly therethrough actuated by telescoping said upper and lower portions.

8. In a device of the character described, a ported flow line comprising an upper tubing section and a lower tubing section telescopically connected, a valve closing the bore of the upper portion to pressure therebelow, and a valve structure connected in said flow line and actuated by said sections upon telescopic movement thereof to close the port and open communication between said sections.

9. A circulation valve assembly adapted for use with pipe in an oil well or the like consisting

essentially of two conduit members telescoped and secured together for limited relative movement longitudinally, said members having means for conducting fluid from end to end thereof when telescoped together, means for preventing flow of fluid from end to end thereof when extended, means for conducting fluid from the interior to the exterior thereof when extended, and means for controlling relative movement between said members longitudinally.

10. In a device for use in a well shaft, a flow line comprising a pair of telescoping sections, a packer carried by said flow line to seal the latter with the well shaft, means to communicate the flow line above the packer with the zone of the well shaft above the packer, and means operable by telescopic movement of said sections to close off said last-named means of communication and open the flow line for communication of the area of the well shaft below said packer with the well surface.

11. In a device for use in a well shaft, a flow line comprising a pair of telescoping sections, a packer carried by said flow line, means of communication, comprising a port in one of said sections, between said flow line and the area of the well shaft above said packer, means to prevent

the flow of fluid through said flow line from end to end thereof, and means to close said means of communication and open said flow line to communication from end to end thereof through said port.

12. In a device of the character described, a pair of tubular members, means for connecting said members together for limited relative longitudinal movement, and a single valve associated with said members to control, selectively, communication of the lowermost of said members with the well shaft above the packer and with the bore of the upper member.

13. In a well testing device for use in a well shaft, a pair of telescopically connected tubular members, one of said members forming a head for a packer and having a lateral port therein communicating the bore of the lowermost tubular member below the packer with the well shaft above the packer through said head, and a single valve member movable in said head and actuated by telescopic contraction of said tubular members to close said communication with the well shaft and open communication between said tubular members through said head.
